SPACE CONDITION RESPONSIVE INSTRUMENT

Leo F. Wildgen, Minneapolis, Minn., assignor to Honeywell Inc., Minneapolis, Minn., a corporation of Delaware

Filed July 26, 1965, Ser. No. 86,291

Term of patent 14 years

(Cl. D52—7)

FIGURE 1 is a front view of my design for a space condition responsive instrument;

FIGURE 2 is a side view of my design looking from the left of FIGURE 1;

FIGURE 3 is a top view of my design looking at the top of FIGURE 1;

FIGURE 4 is a partial cut-away of the top view of my design as shown in FIGURE 3; and

FIGURE 5 is a partial cut-away side view of the side view shown in FIGURE 2.

The undisclosed side of the instrument and bottom thereof are substantially the same in appearance as the side and top shown.

The essential features of my disclosed design reside in the portion shown in full lines in the drawing.

I claim:

The ornamental design for a space condition responsive instrument, substantially as shown and described.
